F. A. KING,

ELECTRIC SWITCH LOCK,

APPLICATION FILED APR. 27, 1917.

1,290,233.

Patented Jan. 7, 1919.

Fig. 4.

Frank A. Kissell Inventor

By Attorney

UNITED STATES PATENT OFFICE.

FRANK A. KING, OF DENVER, COLORADO.

ELECTRIC-SWITCH LOCK.

1,290,233.

Specification of Letters Patent.

Patented Jan. 7, 1919.

Application filed April 27, 1917. Serial No. 164,855.

To all whom it may concern:

Be it known that I, FRANK A. KING, a citizen of the United States, residing in the city and county of Denver and State of Colorado, have invented certain new and useful Improvements in Electric-Switch Locks; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates generally to improvements in switches or make and break devices which are well adapted for use on automobiles for forming the electrical connection with the storage battery or the magneto as may be required. It will be understood that the storage battery on an automobile is employed to produce the electric spark required for igniting the mixture in the cylinders of the engine before the latter is started and consequently before the magneto is in operation. Hence when the machine is originally started, the sparking apparatus is placed in circuit with the storage battery, while after the engine is started the connection is made with the magneto.

My object is to provide a structure of this class which cannot be tampered with. The structures in common use, may be taken apart in such a way that access may be gained to the movable contact whereby the latter may be adjusted by hand for the purpose of starting the engine, thus making it impossible for an unauthorized person to make this adjustment and steal the automobile. In my improvement, I make provision whereby it is impossible for anyone to tamper with the switch since it is necessary to employ a key for unlocking a lock which forms a part of the device, before the contact may be shifted from the neutral position, into position for operating the ignition mechanism. Hence my improvement relates more particularly to the safety or locking feature of a switch of this character.

Having briefly outlined my improvement, I will proceed to describe the same in detail, reference being made to the accompany-

ing drawing in which is illustrated an embodiment thereof. In this drawing:

Figure 1 is a top plan view of a switch provided with my improvement.

Fig. 2 is a section taken on the line 2—2 Fig. 3 looking toward the left.

Fig. 3 is a section taken on the line 3—3 Fig. 2.

Fig. 4 is an underneath view of the switch casing constructed to coöperate with my improved lock mechanism.

Fig. 5 is a top plan view of a washer forming a part of the structure.

Fig. 6 is an inner end view of the lock proper.

Fig. 7 is a side elevation of the lock.

The same reference characters indicate the same parts in all the views.

Let the numeral 5 designate the insulating body member of the switch in which is mounted a central pivot pin 6 having a flanged base 7 embedded in the body 5. This pin forms the pivot for the adjustable member 8 whose body portion 9 is composed of insulating material and whose central portion 10 is composed of metal and perforated to receive the pivot pin 6. The two parts 9 and 10 of the adjustable member or switch block, are connected to move in unison upon the pin 6 during the adjustment of the switch for the purpose of making and breaking the electrical connection either with the storage battery or the magneto (not shown). This switch block is further equipped with a metal contact 12 which consists of a segment which when in the neutral position (see Fig. 2) is disconnected from both sources of electricity. It may then be said to be in the neutral position and is in engagement with a spring contact 13 which has a base 14 secured to the insulating body 5 as shown at 15 and 16. When the contact 12 is moved toward the left to the dotted line position in Fig. 2, one extremity is brought into engagement with a spring contact 17, while its opposite extremity is still in engagement with the spring contact 13. Under these circumstances, the circuit is established by way of electrical conductors 18 and 19, with the storage battery for instance. Again, when the contact 12 is moved toward the right, one of its extremi-

ties may be brought into engagement with a spring contact 20, while its opposite extremity is still in engagement with the spring contact 13. In this event, the circuit 5 through the spring contact 17 will be broken, and a circuit established by way of electrical conductors 21 and 22, with the magneto for instance.

My object is to prevent this adjustment 10 of the movable member of the switch except by an authorized person and my improvements whereby this result is accomplished will now be described in detail.

My improved construction includes a casing 23 which surrounds the insulating base 5 of the switch and extends above the same, the top part 24 being slightly arched or upwardly inclined toward the center finally merging into a cylindrical member 25 which 20 is open at the top to receive a cylindrical part 27 of a spider member which includes three arms 28, 29 and 30 whose extremities are perforated to receive screws 31 through the medium of which the spider is securely 25 anchored to the insulating body 5 of the switch, the body member being provided with inwardly projecting lugs 32 for the purpose. When the casing is applied, this spider member together with the fastening 30 screws, is entirely concealed.

The inner surface of the top 24 of the casing is provided with a depending hook shaped lug or projection 33 which is adapted to receive a lip 34 formed on a washer 35 whose opening 36 is of such size as to fit 35 closely around the upper portion of the central metallic part 10 of the body member of the switch. This metal part 10, however, is slotted on opposite sides from the top downwardly or inwardly to receive two inwardly projecting lugs 37 of this washer, whereby when the washer is in place it is locked upon the adjustable member 8 of the switch and must move therewith. Normally, or when the switch is in the neutral 40 position, the lip 34 of this washer engages the hook shaped lug 33 of the casing, whereby the casing is locked against removal from the switch. The cylindrical member 27 of the spider terminates a short distance from the top of the cylindrical part of the casing. Fitting within the cylindrical member 27 of the spider is the lock proper designated by the numeral 38 which 45 is provided with a barrel 39 the latter fitting into the upper part of the cylindrical member of the casing and engaging the top of the cylindrical member 27 of the spider. The inner extremity of the barrel of the lock is provided with oppositely disposed 50 projections 41 which when the parts are assembled, enter the recesses in the top of the metal member 10 directly above the lugs 37 of the washer 35. These projections 41 on the lock barrel are shown in Fig. 2, while

the member 10 is shown in top plan view in this figure. Hence the recesses in the top of the member 10 may be designated by the numeral 42.

The lock 38 when the parts are assembled 70 occupies the position well illustrated in Fig. 3 and the lock is rotatably held in co-operative relation with the member 27 of the spider, by a pin 43 which is passed through the upper part of the cylindrical 75 member 27 of the spider and engages a circumferential groove 44 formed in the lock barrel to permit the rotation of the latter when the tumblers 45 are in the unlocked position. These tumblers 45 protrude into 80 oppositely disposed grooves 46 formed in the member 27 of the spider when in the locked position, but when a suitable key 47 is inserted, the exterior surfaces of the tumblers are made to conform to the curvature of the lock barrel which is slotted on 85 opposite sides to allow the tumblers to protrude.

In the operation of the device, assuming 90 that the movable member 8 of the switch is in the neutral position and that the key is removed from the lock whereby the tumblers protrude into opposite grooves of the spider member 27, it will be impossible to gain access to the switch for the purpose of moving the member 8, until the key is inserted in the lock. As soon as this is done, however, the lock barrel may be turned through the instrumentality of the key which is kept in position, sufficiently 100 to cause the contact member 12 to engage the spring contact 17 or 20 as desired. And when this is done, the lip 34 of the washer 35 will be disengaged from the hook shaped lug 33 of the casing, whereby the casing may be removed from the switch as soon as a screw 48 which is inserted in the top of the casing and threaded into the arm 30 of the spider, is removed. But it will be noted that until the device is unlocked and the lip 34 shifted by turning the lock or the barrel through the medium of the key, the lip 34 of the washer will prevent the removal of the casing, and hence will prevent access to the switch for the purpose 110 of moving the arm 8.

It will be understood that the invention is not limited to any particular construction of lock though that illustrated in the drawing is suitable for the purpose. 120

Having thus described my invention, what I claim is:

1. A mechanism including a body member, a second member movable thereon, a third member secured to the body member and merging into a cylindrical part at the top, a lock arranged within said cylindrical part of the third member and connected in operative relation with the second member, a casing, a direct interlocking connection 125 130

between the second member and the casing when the second member is in a predetermined position, and an operative connection between the lock and second member 5 for actuating the latter to unlock the casing.

2. A mechanism comprising a body member, a second member movable thereon, a spider secured to the body member and merging at its upper extremity into a cylindrical part, a lock arranged within said cylindrical part and connected in operative 10 relation with the second member, a casing

and a direct interlocking connection between the second member and the casing whereby when the second member is actuated through the medium of the lock, the casing is released. 15

In testimony whereof I affix my signature, in presence of two witnesses.

FRANK A. KING.
